Specification for Design.

Patented Apr. 4, 1922.

Application filed January 9, 1922. Serial No. 139. Term of patent 3½ years.

To all whom it may concern:

Be it known that I, MAUD E. McCASKILL, a subject of the King of Great Britain, residing at Los Angeles, in the county of Los Angeles and State of California, have invented a new, original, and ornamental Design for a Hat, of which the following is a specification, reference being had to the accompanying drawing, forming part thereof, in which the figure is a perspective view of the hat showing my new design applied to the head of an individual.

I claim:—

The ornamental design for a hat as shown.

MAUD ETHEL McCASKILL.
